[57] CLAIM

The ornamental design for a golf club putter head, as shown and described.

DESCRIPTION

FIG. 1 is a left side elevational view of a golf club putter head showing my new design;

FIG. 2 is a rear elevational view thereof;

FIG. 3 is a rear and left side perspective view thereof;

FIG. 4 is a front elevational view thereof;

FIG. 5 is an enlarged, top plan view thereof;

FIG. 6 is an enlarged bottom view thereof; and,

FIG. 7 is an enlarged, front and left side perspective view thereof.

The broken line showing of a shaft and grip are for illustrative purposes only and form no part of the claimed design.
